UNITED STATES PATENT OFFICE.

KENNETH H. SAUNDERS, OF BRATTLEBORO, VERMONT, ASSIGNOR TO MILLERS FALLS COMPANY, OF MILLERS FALLS, MASSACHUSETTS, A CORPORATION OF MASSACHUSETTS.

JACK.

Application filed January 12, 1925. Serial No. 1,815.

To all whom it may concern:

Be it known that I, KENNETH H. SAUNDERS, a citizen of the United States, residing at Brattleboro, in the county of Windham and State of Vermont, have invented certain new and useful Improvements in Jacks, of which the following is a full, clear, and exact description, such as will enable others skilled in the art to which it appertains to make and use the same.

This invention relates to an improved type of jack.

It is an object of the invention to provide a device of the character stated which may have its parts normally disposed within a relatively small amount of space, but which when extended will elevate an article which is to be lifted to a comparatively great extent.

20 A further object of the invention is that of providing a jack particularly adapted to form a part of an automobile tool kit, and by means of which the axle or other part which is to be elevated may be lifted with an expenditure of a minimum amount of energy and a small amount of time, whereby the device is of particular value when it is necessary, for example, to change a tire having a large body such as is usually the case 30 in connection with low pressure or so-called balloon tires.

Another object is to be predicated on the provision of an article of the nature stated which when in use will efficiently support the parts which it has served to elevate and in such a manner that there will exist virtually no danger of this support being withdrawn incident to the accidental displacement of the jack.

40 An additional object is that of providing a jack which will efficiently perform the purposes for which it is intended, and which will also be economically and readily manufactured and assembled.

45 Other objects of the invention will in part be obvious and will in part appear herein-after.

The invention accordingly comprises the features of construction, combination of elements and arrangement of parts which will be exemplified in the construction herein-after set forth, and the scope of the application of which will be indicated in the claims.

For a fuller understanding of the nature

and objects of the invention reference should be had to the following detailed description taken in connection with the accompanying drawings, in which:

Fig. 1 is a top view of one type of jack embodying the improved construction of the present invention;

Fig. 2 is a partly sectional side view thereof; and

Fig. 3 is a partly sectional front view of the same.

The particular jack in which the invention is exemplified comprises a base 5 formed with laterally-extending supports 6 at its lower end. The upper portion of this base is provided with a pair of threaded bores adjacent either side thereof, and into these bores extend a pair of lifting screws 7 and 8. The upper ends of the screws are reduced, as indicated at 9, and extend through annular bearings 10 carried by a vertically movable platform in the nature of a plate 11 adapted to support the operating mechanism of the jack. This mechanism comprises in the present instance a pinion 12 which may be rotated by means of a bolt 13 rotatably supported by the plate 11, and which is provided with a squared head 13' extending outwardly therefrom so that the pinion may be operated from a position lateral with the jack.

85 The periphery of the pinion 12 is beveled, and its teeth are adapted to mesh with the teeth of a horizontal beveled gear 14, which encircles a spur gear 15 and is lockingly supported thereon by any suitable means such as screws 16. The gear 15 is in turn rotatably supported on the plate 11 in any desired manner, as by ball bearings 16'. Meshing with the gear 15, in the present construction, is a pair of spur gears 17 and 18, which are rigidly secured to the reduced portions 9 of the screws 7 and 8, respectively. The gear 15 has a screw-threaded bore 19, the threads of which are adapted to cooperate with the threads of an upper lifting screw 20, and a knurled lifting head 21 is associated with the upper end of this screw, so that the article to be lifted may be securely supported.

100 In the present instance the threads of the screw 20 are interrupted by a keyway 22, which extends substantially throughout the length of the screw, and a cooperating key 23 forms a part of a strap 24 which is

rigidly secured to the plate 11. The base 5, moreover, is so constructed as to present an unobstructed path, such as the bore indicated at 25, within which the screw 20 may be telescoped.

The mode of operation of the particular device described above will now be apparent. The jack will be inserted under the article to be lifted and the pinion 12 rotated by any desired expedient. The rotation of the pinion will result in the rotation of the horizontal beveled gear 14 and a corresponding movement of the central spur gear 15. Thus, due to the fact that the screw 20 is prevented from rotating, the latter will be moved in a vertical plane with respect to the platform. At the same time the gears 17, 18, and, consequently, the screws 7, 8, will be turned, which will result in the platform being vertically moved with respect to the casing.

Thus, a double lifting movement will be transmitted to the article supported on the head 21, part of this movement being imparted to the screw 20 by the upward movement of the supporting and lifting screws 7 and 8, and the other part of the movement resulting from the upward movement of the screw 20 with respect to the gear 15 and the plate 11. It will be observed that by employing the two lifting screws 7 and 8 on opposite sides of the screw 20, the particular jack exemplified is exceedingly sturdy and gives a maximum of support to an article held thereby, and that by the particular arrangement of gears there is obtained a jack which is exceedingly efficient in operation and which may be assembled with the utmost ease.

It will also be seen that, due to the fact that the lifting screws are in the present instance arranged in a row, which extends at right angles to the foot portions of the base, an accidental displacement of the jack in one direction will be prevented by these latter operations, while a displacement in another direction will be prevented by the arrangement of the lifting screws.

Thus the objects of this invention have been accomplished, and since certain changes may be made in the above construction, and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I

claim as new and desire to secure by Letters Patent is:

1. In a jack, in combination, three screws, means for mounting the same, and a plurality of intermeshing gears operatively connected one with each of said screws, said gears being adapted to simultaneously operate all of said screws to impart corresponding movement to two of the same and a movement to the third screw dissimilar to the movement imparted to the first two screws, certain of said gears being fixed against movement with respect to the screws with which they are associated. 70

2. In a jack, in combination, a plurality of lifting screws arranged beside one another, and a number of intermeshing gears, one of said gears being fixedly associated with one of said screws, another of said gears being operatively connected with, and rotatable with respect to, a second of said screws. 80

3. In a jack, in combination, a plurality of lifting screws arranged beside one another, and means for simultaneously operating the same, said means including a gear having a threaded connection with one of the screws and a gear fixedly attached to another of the screws. 90

4. In a jack, in combination, a non-rotatable screw and a rotatable screw arranged side by side, a gear operatively connected with, and rotatable with respect to, said first-named screw, and a second gear cooperating with said first-named gear and fixedly connected with said second screw. 100

5. In a jack, in combination, a plurality of lifting screws mounted for simultaneous rotation, another screw mounted for axial movement, and means for actuating said screws. 105

6. In a jack, in combination, a lifting screw, a gear having a threaded connection therewith, a second lifting screw arranged to one side of said first screw and connected therewith, and means including said gear to operate said screws. 110

7. In a jack, in combination, a projectable member, a second projectable member operatively connected with the aforesaid member and to one side of the same and means for operating said members. 115

8. In a jack, in combination, a non-rotatable member, a pair of lifting screws extending from opposite sides of said member, one of said screws being rotatable with respect to the same, the other of said screws being adapted to be moved in a solely axial direction, and means for operating said screws. 120

9. In a jack, in combination, a train of gears, a pair of lifting screws arranged beside one another, one of said screws having a threaded connection with one of the gears of said train, another of said screws being fixedly secured to a second of said gears, 125

130

means for operating said gears, and a support for said second screw having a threaded opening for engagement therewith.

10. In a jack, in combination, a plurality 5 of projectable members, another projectable member supported between the aforesaid members, and means for simultaneously operating said members, said means including a plurality of intermeshing gears, one of 10 said gears being fixedly connected with one of said members, another of said gears being rotatably associated with a second of said members.

11. In a jack, in combination, a screw 15 mounted for rotation, a screw mounted solely for axial movement, and means to cause simultaneous positive and relative movement of said screws in a given direction.

12. In a jack, in combination, a plurality 20 of screws, the threads of which are pitched in the same general direction, and means to cause simultaneous positive and relative movement of said screws in a given direction, said means comprising a plurality of 25 intermeshing gears operatively connected to said screws, one of said gears being fixed with respect to the screw with which it is connected.

13. A double lift jack, comprising an axial- 30 ally movable upper lifting screw, a plurality of rotatable lifting screws adapted to support the aforesaid screw and means for operating said screws.

14. In a jack, in combination, a gear 35 train, a screw threadedly connected to one of the gears of said train, a non-rotatable member, and a screw rigidly secured to another of said gears, said latter gear meshing with the first-mentioned gear, and said lat-

ter screw being threadedly connected with said non-rotatable member.

15. In a jack, in combination, a pair of intermeshing gears, means to rotate said gears, a screw threaded through the interior of one of the gears, means to prevent the rotation of the screw, a stationary member, and a screw rigidly secured to the other of 45 said gears and threaded into said stationary member.

16. In a jack, in combination, a pinion, a gear meshing therewith, a spur gear concentric with the aforesaid gear and rotatable therewith, a second spur gear meshing with the aforesaid spur gear, and a lifting screw 50 operatively connected to each of said spur gears.

17. In a jack, in combination, a pair of screws, means for mounting the same beside one another, a pair of intermeshing gears 55 operatively connected one with each of said screws, and means for operating said gears to turn and project one of said screws and to move the second of the same solely in an axial direction.

18. In a jack, in combination, a plurality 60 of intermeshing gears, a support therefor, gear-operating mechanism carried by said support, a screw threadedly connected to one of said gears, a keyway formed in said screw, a key carried by said support and extending into said keyway, a base, and a further screw arranged beside said first-named screw and threaded into said base, said further screw being rotated by another of said 65 gears.

In testimony whereof I affix my signature.

KENNETH H. SAUNDERS.
